UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed June 27, 1924, Serial No. 722,666. Renewed April 5, 1926.

This invention relates to telephone exchange systems, and more particularly to systems employing automatic switching apparatus in the extension of conversational 5 connections.

The object of this invention is to enable a repetition of the testing of a group of lines or trunks due to the fact that such group has been previously tested and all lines or trunks 10 therein have been found unavailable.

A feature of the invention relates to a system having a number of testing equipments, each arranged for connection to a group of trunks outgoing from a selective switch, together 15 with means for disconnecting from said group a testing equipment which has found all trunks therein busy and for automatically connecting to such group either the same or another testing equipment for 20 the purpose of making a repeated test of said trunks.

A further feature relates to a system in which a sender is connected to one of a number of markers and the connected marker is 25 then connected to a group of trunks, said markers each having means for making a test of said trunks, together with means for disconnecting the marker both from the sender and from the trunk group if all 30 trunks are found busy and for automatically connecting either the same or another marker both to said sender and to said group of trunks to make a further test of said trunks.

Referring to the drawing, Figs. 1 to 10, 35 inclusive, taken in the order illustrated in Fig. 11 disclose a portion of a central office telephone system incorporating the features of this invention.

Fig. 1 shows schematically a subscriber's 40 line, a line switch, an outgoing trunk, a sender selector switch, and a portion of a subscriber's sender.

Fig. 2 shows a district selector switch in 45 which terminate trunks leading from the line switches.

Fig. 3 shows an office selector switch to which trunks from the district selector switch lead and which has access to trunks outgoing to succeeding switches.

Fig. 4 shows a portion of one of a number 50 of register senders.

Fig. 5 shows a multi-contact relay connecting device for associating the register senders with the markers.

55 Figs. 6, 7 and 8 illustrate one of a num-

ber of controlling markers, the function of which is to determine the selective and testing operation of the district and office switches.

Fig. 9 shows a frame connector for connecting the markers to the frames of the district switches and also a trunk connector for associating the marker with the different groups of trunks outgoing from the district switches.

Fig. 10 illustrates a frame connector and a trunk connector for the office selector switches.

The system disclosed herein is an improvement upon the type of system shown and described in the patent to S. B. Williams, No. 1,517,331, granted December 2, 1924, and in the application of W. W. Carpenter, Serial No. 703,362, filed April 1, 1924, to which reference is hereby made for an understanding of the various operations which may hereinafter be referred to but not specifically described.

In systems of this type where markers are associated with register senders and also with the particular selective switch at which the selective operation is to take place, and wherein the marker is provided with equipment for making a test of the trunks in the selected group in order to ascertain an idle 80 one before directing the operation of the switch to select such a trunk, it may frequently occur that the marker at the time of making the test finds that none of the trunks in the desired group is available. Heretofore, when this condition was encountered, it was impossible to proceed further with the establishment of the connection, and usually a busy signal was transmitted to the calling subscriber to advise him that the call could 90 not be completed.

According to the present invention, however, if a marker at the time of making a test of the trunks in the selected group at any selective stage, finds all of the trunks to 100 be simultaneously busy or otherwise not selective, it automatically releases from the register sender to which it is connected and also from the group of trunks to which it is connected. Thereupon, the sender immediately seizes either the same or another marker and governs it in such a manner that it becomes associated with the proper selective switch and with the same group of trunks again for the purpose of making a repeated 110

test to ascertain if, in the meantime, any one of such trunks has become idle. This procedure may be repeated a number of times until an idle trunk is found, or if after having made a predetermined number of repetitions no trunk is found to be idle, then the usual busy signal may be transmitted to the calling subscriber.

10 *General description of the apparatus and of the operation.*

11 The calling subscribers' lines, such as the line 100, terminate in vertical rows of contacts in coordinate line switches 101. These switches have access to groups of trunks, such as the trunk 102, which extend and appear in vertical rows of contacts in coordinate district selectors. The trunk 102, for instance, appears in the vertical row 201 of the district selector 200. Another trunk 214 similarly occurs in the vertical row of contacts 202, and still other trunks, of course, may be provided.

23 The district selector switch 200 contains a number of vertical rows of contacts 203, 204, etc., in which appear numerical groups of trunks outgoing to succeeding switches. The group occurring in the row 204, for example, contains trunks which lead to office 30 selectors 300.

25 The trunks incoming from the district selectors terminate in vertical rows of contacts 301, 302, etc., of the coordinate office selectors 300. These office selectors in turn have groups of trunks appearing in rows 303, 304, etc., which lead out of the office and to switches or other equipment in distant offices.

40 Each of these coordinate switches comprises a plurality of intermediate or horizontal links, together with vertical and horizontal selecting and operating bars and individual magnets for operating these bars. The district switch 200, for example, has a number of links 205, 206, 207, 208, etc., with individual operating bars 215, 216, 217, and 218 and the respective horizontal operating magnets 219, 220, 221 and 222. Furthermore, the switch has vertical bars 209, 223, 50 213, etc., together with corresponding operating magnets 210, 211 and 212.

55 The office selector switches are similarly constructed including horizontal links 305, 306 and 307, together with the horizontal bars and vertical bars and operating magnets.

60 The trunks such as 102, leading from the line switches to the district selector, also appear in coordinate sender selector switches 108 which have access to a number of recording senders, one of which is shown partially in Fig. 4 and Fig. 1.

65 The register senders appear in sender connecting devices 500, each different sender being represented by a different multi-contact

relay 503, 504, etc. The device 500 is also provided with a number of relays 510, 512, etc., each of which represents a different one of the controlling markers. By operating the proper pair of these relays, any sender 70 may be connected to any marker.

75 The marker includes a number of registers 600, 601, and 602 which receive the office portion of the entire designation, which is made up of three separate digits, from the register sender. Furthermore, a translating device 603 is made up of a number of sets of multi-contact relays 610, 611, 612, etc., and 613, 614, 615, 607, 608, 609, etc. The registers 600, 601, etc., cooperate with this translating device in such a manner as to determine the selection of the group relays 712, 713, 714, 715, etc. These group relays determine the particular groups of trunks at the district and office switches 85 which must be involved to route the call in the direction corresponding to the designation transmitted to the sender.

90 The marker also determines the selection and operation of the proper one of the frame 99 connectors 900 in order to associate itself with the group of district frames 200 containing the frame in which appears the trunk over which the connection has been extended from the calling line. This frame connector 900 includes a number of relays 902, 903, each individual to a different one of a plurality of markers. It also comprises a number of relays 904, 905, etc., each individual to a particular district frame 200 in 100 the group. Relay 905, for instance, is individual to the frame 200 shown in the drawing.

105 The trunk connector 901 comprises a number of relays 910, 911 each individual to a different marker. The connector 901 in addition includes a number of relays 912, 913, etc., each of which is individual to a different group of trunks outgoing from the district frames 200. The trunks of each group may be multiplied to appear in as 110 many selectors as is desirable.

115 In a similar manner, the office frame connector 1000 and the trunk connector 1001 comprise a number of corresponding multi-contact relays.

120 The marker is equipped with a testing device constituted of a number of sets of testing relays 800. These relays serve to test the horizontal links and the corresponding outgoing trunks of any group at either the district or the office switches. In other words, they are first associated with the district switch to test and select an idle trunk and its corresponding idle link and then they are subsequently associated with the proper office switch to perform a similar function.

125 Another function of the marker is to determine from the office code registration which it receives from the sender, the na 130

ture or class of the connection that is to be extended. This it does through the medium of the translator 606 and may cause the operation of one of a number of class 5 relays 628. These class relays or the translator itself may directly cause the closure of a circuit extending back into the sender for the operation of the proper class relays in the sender, thus giving the sender the 10 necessary information to enable it to be prepared to exercise the necessary control over the connection involved. The class relays in the marker may also cause the completion of circuits leading through a special 15 horizontal link 224 of the district selector to operate certain relays located in the trunk circuit 102.

The line switch 101, selector switches 200 and 300, and the sender selector switch 108 20 may be of the general construction and operation as those shown and described in the patent to C. L. Goodrum and J. N. Reynolds, No. 1,515,735, granted November 18, 1924, and the patent to S. B. Williams, No. 25 1,517,331, granted December 2, 1924.

Detailed description of the establishment of a connection.

It will now be assumed for the purpose of 30 describing the invention that the subscriber of line 100 wishes to obtain a connection extending through the district and office selector switches 200 and 300. The calling subscriber in initiating the call, causes the 35 operation of line switch 101 to extend his line over an idle trunk 102 to the district switch 200. The initiation of the call also causes the operation of the sender selector switch 108 to associate the trunk 102 with the idle register sender shown in the drawing. During the operation of the sender selector switch 108, a circuit is completed for 40 operating the relay 104. The relay 104 completes a holding circuit for the slow-release relay 106 which has been previously operated. This holding circuit leads through 45 the lower contact of relay 104 and the locking contact of relay 106. As soon as the sender selector switch 108 and the line switch 50 101 have operated, the subscriber's line is included in series with the impulse relay 400 in the sender. The circuit for this purpose may be traced from battery, through the right winding of relay 400, outer right contact 55 of relay 410, thence through the sender selector switch 108 over the ring of the trunk 102, through the line switch 101 over the loop of the line 100, and returning 60 through the line switch 101 and sender selector switch 108, inner right contact of relay 410, to ground through the right winding of balancing coil 403. Relay 400 operates and closes a circuit for the slow-release holding relay 401. Relay 401 completes operating circuits for the relays 402 and 416.

These relays lock in circuits from battery, through their windings, thence through the inner right contact of relay 402, left contact of release relay 410, to ground at the inner left contact of relay 402. The relay 402 70 applies ground potential through its inner left contact, left back contact of relay 410, to the conductor 417, which serves to hold the sender selector switch 108 and the relay 104 in operated condition. 75

Recording the designation in the sender.—The subscriber now manipulates his dial (not shown) to transmit a number of series of impulses representing the wanted designation. The impulse relay 400 responds to these impulses and cooperates with relays 405, 406, 407, 408 and 409 and with a set of counting relays diagrammatically illustrated by the rectangle 404 to cause the setting of a corresponding number 80 of registers illustrated diagrammatically by the rectangle 109. The general manner in which the foregoing operations may be accomplished is described and illustrated in the patent to S. B. Williams, No. 1,517,331, 85 granted Dec. 2, 1924. 90

Association of sender with an idle marker.—As soon as the first three sets of registers 109 have been operated, a circuit is closed extending over conductor 418, 95 through the winding of relay 413, to battery. Relay 413 causes the energization of relay 501 to initiate the operation of the connector 500. The circuit for this purpose may be traced from battery, through the lower contact of relay 502, left winding of relay 501, conductor 513, contact of relay 411, outer right back contact of relay 414, left contact of relay 413, conductor 420, conductor 421, to ground at the outer contact of holding relay 416. Relay 501 operates and closes a holding circuit from battery, through the winding of relay 502, right front contact and right winding of relay 501, to ground over the circuit above 100 traced. Relay 501 holds and relay 502 operates in this latter circuit. Relay 502 in operating, prevents the operation subsequently of another relay similar to the relay 501. With relay 501 operated, multi-contact relay 503 is energized in a circuit from battery, through its winding, left contact of relay 501, upper contact of relay 505, to ground at the inner lower contact of relay 502. Relay 503 locks through its own contact to ground at the upper contact of relay 502. 110

Relay 502 completes a start circuit to select the first idle one of the markers. Assuming that the marker appearing in the multi-contact relay 512 is busy and that the next marker illustrated is idle, this start circuit leads from ground, through the inner lower contact of relay 502, inner contact of relay 505, left front contact of relay 125 130

720, conductor 721, through the distributing frame 634, contact of relay 612, lower contact of relay 607, conductor 635, to ground at the outer right contact of relay 708. Relay 714 locks through its own contact, conductor 722, inner right back contact of relay 706, to ground at the contact of relay 700.

The relay 714 represents the group of trunks out-going from the office switch 300 in the desired direction, as for example the group appearing in the vertical row 304. Relay 714, moreover, causes the operation of the district selector group relay 712 in a circuit from battery, through the winding of relay 712, contact of relay 714, middle right contact of relay 707, outer left contact of relay 708, to the grounded conductor 722. Relay 712 represents the group of trunks appearing in the vertical row 204 of the district selector 200 which extend to the office selector switch 300.

In case class information is necessary for the sender, the class relay 636 may be operated in a circuit from battery, through its winding, contacts of relays 612, upper contact of relay 607, to the grounded conductor 635. Relay 636 applies ground potential to conductor 638, which extends through the connector 500, thence over the conductor 520, through the winding of class relay 441 to battery. Relay 441 operates and locks to conductor 420 and later serves to govern the operation of the register sender in a manner suitable for the particular class of call being extended.

Operation of the district frame connector.—At the time relay 604 operates, it closes an energizing circuit for the relay 907 of the frame connector 900. This circuit may be traced from battery, through the outer right contact of relay 704, conductor 723, winding of relay 907, conductor 919, back contact of relay 725, conductor 726, outer right contact of relay 604, conductor 640, through the connector 500, conductor 110, right back contact of relay 422, conductor 423, thence over conductor 111, through the connector 500, to ground over conductor 719, as previously traced. Relay 907 completes a circuit for relay 906, traceable from battery, through the right winding of the latter relay, front contact of relay 907, back contact of relay 920, (assuming this relay to be de-energized), upper contact of relay 909, to ground at the back contact of slow-release relay 908. When relay 906 has operated, it operates slow-release relay 908 in a circuit from battery, through the winding of relay 908, lower back contact of relay 909, right contact of relay 906, conductor 921, conductor 922, outer left contact of relay 711, middle right contact of relay 707, outer left contact of relay 708 to the grounded conductor 722. The relay 908 operates and opens the

operating circuit of relay 906. Relay 906 being slightly slow-to-release, however, remains energized until relay 908 has fully operated. A holding circuit for relay 906 is then closed from battery, through the left contact of relay 906, left back contact of relay 923, winding of relay 909, to ground at the front contact of relay 908. Relay 909 operates and opens the circuit of relay 908. Relay 908 releases and operates the multi-contact relay 902. The circuit for this purpose leads from battery, through the winding of relay 902, outer left contact of relay 906, upper front contact of relay 909, to ground at the back contact of relay 908. Relay 909 being operated, prevents the operation of another of the relays 906, 923, thereby avoiding interference by other markers. After relay 908 releases, relays 906 and 909 remain operated in a circuit which leads through the lower front contact of relay 909, right contact of relay 906, to the grounded conductor 921.

The vertical operating magnet 210 controlling the row of contacts 201 in the switch 200 in which appears trunk 102, is now operated. The circuit may be traced from battery, through the winding of said magnet, conductor 227, left back contact of relay 107, through the switch 108, conductor 112, connector 500, conductor 521, normal contact of relay 703, inner left back contact of relay 710, conductor 727, contacts of the connector 900, outer left contact of relay 711, middle right contact of relay 707, outer left contact of relay 708 to the grounded conductor 722. The magnet 210 rotates the vertical bar 209 and prepares all contacts in the row 201. Magnet 210 closes a circuit for the horizontal operating magnet 226. This circuit is closed after the bar 209 has fully rotated and results in the connection of the link conductors 224 to the contacts in the vertical row 201 for a purpose to be described hereinafter. Magnet 210 also extends the grounded conductor 227 through its inner lower contact over conductor 228, through the winding of the multi-contact relay 905, to battery. Relay 905 which is individual to the switch 200, operates and results in the connection of the conductors from the marker through to the frame of the selector switch 200.

With the frame connector 900 operated, relay 703 in the marker is energized in a circuit from battery, through the winding of said relay, outer left back contact of relay 710, conductor 730, through the frame connector 900, to ground over the conductor 922, as previously traced. Relay 703 at its normal contact opens the operating circuit of magnet 210, but before this occurs, said relay closes a substitute holding circuit for said magnet and also for relay 905, at the make-before-break contact of said relay 703.

The holding circuits may be traced from battery, through the winding and contact of magnet 210, conductor 228, and in parallel thereto from battery, through the winding 5 and contact of relay 905, contact of relay 902, conductor 924, conductor 925, make contact of relay 703, and thence over conductor 727 as previously traced, to ground.

With the conductors of the horizontal link 10 224 connected to the contacts in the row 201, a circuit is closed for the relay 107 in the trunk circuit. The circuit for relay 107 may be traced from battery, through the winding thereof, conductor 113, contacts of the switch 15 200, conductor 229, through the frame connector 900, conductor 926, left contact of relay 703, to ground at the outer right contact of relay 708.

Operation of the district trunk connector.—During the foregoing operations, the 20 district trunk connector 901 is also being operated for the purpose of connecting the test relays 800 with the proper group of trunks outgoing from the district selector 200. For starting the trunk connector 901 in operation, the relay 915 is energized in a 25 circuit from battery, through the winding of said relay, conductor 927, outermost contact of group relay 712, conductor 728, outer 30 right contact of relay 902, upper front contact of relay 909, to ground at the back contact of relay 908. Relay 915 operates the relay 914 in a circuit from battery, through the left winding of relay 914, right front 35 contact of relay 915, back contact of relay 928, upper back contact of relay 917, to ground at the back contact of slow-release relay 916. Relay 914 when operated, causes the operation of slow release relay 916 in a 40 circuit from battery, through the winding of the latter relay, lower back contact of relay 917, left contact of relay 914, to the grounded conductor 921. Relay 916 operates and opens the energizing circuit of relay 914. 45 Relay 914 being slightly slow-to-release, however, retains its armatures until relay 916 fully operates, at which time a locking circuit is closed as follows: battery, through the right winding and contact of relay 914, 50 inner right back contact of relay 929, winding of relay 917, to ground at the front contact of relay 916. Relay 917 operates in this circuit and opens the circuit of relay 916, which subsequently releases. When relay 55 916 releases, the relays 914 and 917 are held energized in a circuit leading through the lower front contact of relay 917, left contact of relay 914, to the grounded conductor 921. The multi-contact relay 910 is 60 now operated in a circuit from battery, through its winding, outer right contact of relay 914, upper front contact of relay 917 to ground at the back contact of relay 916. The multi-contact relay 912, which is 65 individual to the group of trunks appearing

in the vertical row 204 of the district selector 200, is operated in a circuit from battery, through its winding, conductor 930, contact of group relay 712, conductor 731, middle right contact of relay 914, upper 70 front contact of relay 917, to ground at the back contact of relay 916.

Testing links and trunks at the district selector.—The marker is now prepared to proceed with a test of the selected group of 75 trunks outgoing from the district selector 200 and also of the corresponding horizontal links. The right windings of the double wound test relays 801, 802, 803, etc., serve to test the trunks 230, 231, 232, 233, etc., in 80 order. The left windings of these relays serve to test the corresponding horizontal links 205, 206, 207 and 208. The test circuit for the trunk 230 may be traced from battery, through the right winding of relay 801, 85 through a back contact of relay 808, conductor 813, right back contact of relay 806, conductor 814, conductor 1014, through the trunk connector 901, conductor 931, to the sleeve conductor of the trunk 230. The test 90 circuit for the corresponding link 205 may be traced from battery, through the left winding of relay 801, through a back contact of relay 808, conductor 815, through the frame connector 900, conductor 236, to the 95 test conductor of the link 205. In a similar manner, test circuits for the remaining trunks of the group and of the corresponding links may be traced through the windings of the test relays 800. 100

It will be assumed that the trunk 233 is the last trunk of the group appearing in the vertical row 204, and that the testing relay 805 relates to this particular trunk. It will further be considered that the preceding 105 trunks in the group and the preceding links are busy in such combinations that there is no one of these trunks idle simultaneously with the idle condition of its corresponding link. In other words, all of the test relays preceding the test relay 805 either has an energizing circuit for one or both of its windings. The operated testing relays 801, 802, etc., lock through their right windings and contacts in a circuit over conductor 817, 110 through the inner left back contact of relay 708, to the grounded conductor 722.

At the instant the testing operation commenced, a circuit was completed for operating the vertical magnet 212 of the district selector 200. This magnet requires an appreciable interval in which to become operated, and consequently serves to measure the time within which the relays 800 are required to test the links and trunks and to assume their operated or non-operated condition accordingly. The circuit for the magnet 212 may be traced from battery, through the winding thereof, conductor 237, through the frame connector 900, conductor 932, con- 115 120 125 130 135

ductor 933, contact of relay 712, conductor 729, contacts of the trunk connector 901, to the grounded conductor 921. When magnet 212 is operated, it operates the relay 704 in a circuit from battery, through the winding of relay 704, normal contact of said relay, conductor 732, through the frame connector 900, conductor 238, to ground at the contact of magnet 212. The relay 704 locks 10 through its inner right contact, through the inner left contact of relay 708, to the grounded conductor 722.

Relays 808 and 809 are now operated in circuits from battery through their windings, thence over conductor 818, inner left contact of relay 708, to the grounded conductor 722. Relays 808 and 809 disconnect the test relays 800 to prevent their subsequent operation. All of the energized relays, however, which were operated during the test, remain locked to the conductor 817. The relay 820 relating to the idle trunk 233 and link 208 is now operated in a circuit from battery through the winding of relay 25 812, winding of relay 820, left back contact of relay 805, thence through the left front contacts of relays 804, 803, etc., in series, conductor 821, conductor 1015, through contacts of the trunk connector 901, conductor 30 934, normal contacts of relay 705, contacts of relay 707, conductor 818, front contacts of relay 704, thence over conductor 817, to ground as previously traced. Relay 812 also operates in this circuit.

35 The horizontal magnet 222 is next operated by means of a circuit from battery through the right winding of said magnet, conductor 239, connector 900, conductor 935, middle left contact of relay 820, to the grounded conductor 817. Another circuit 40 for magnet 222 may be traced from battery through both windings thereof, thence over conductor 234, through the connector 900, conductor 936, next to the lower front contact of relay 809, innermost left contact of relay 820, to grounded conductor 817. The closure of this latter circuit also results in placing a ground potential upon the test conductor of the horizontal link 208. Magnet 55 222 rotates the bar 218 and effects connection from the trunk 102 through link 208 to the trunk 233.

55 Returning to the point where relay 704 operates, it will be noted that this relay causes the release of the translator and marker register relays. Relay 704 at its left contact removes ground potential from conductor 719, causing the release of relay 604 and consequently the release of relays 607, 608, 612, 615 and 636. Relay 704 also causes the release of the operated relays of the registers 600, 601 and 602. The operation of relay 704 also opens the holding circuit of relay 907.

65 During the time the translator relays are

operated, a circuit has been closed for the relay 810 in the marker traceable from battery through the winding of said relay, conductor 819, to ground at the contact of the class relay 636. Relay 810 operates and locks to the grounded conductor 722.

Operation of the office frame connector.— Since the selection has taken place at the district switch 200, it now becomes necessary to release the testing relays 800 to disassociate the marker from the district frame and to associate the marker with the office switch 300, in order to perform a similar testing operation thereat. The frame connector 1000 is started in operation by energizing the relay 1007. The circuit for this relay may be traced from the grounded conductor 817, conductor 822, outer left contact of relay 820, outer left contact of relay 810, conductor 823, through the district 80 trunk connector 901, conductor 937, through the winding of relay 1007, conductor 734, to battery at the normal contact of relay 711.

Since the district trunk connector 901 will presently release, the relay 1007 is locked in a circuit which leads through its winding and right front contact, conductor 1019, to the grounded conductor 722. Relay 1007 operates the relay 1004 in a circuit from battery through the right winding of relay 1004, left front contact of relay 1007, left back contact of relay 1018, upper back contact of relay 1006, to ground at the back contact of slow-release relay 1005. Relay 1004 operates and causes the energization of relay 1005 in a circuit from battery through the winding of the latter relay, back contact of relay 1006, right contact of relay 1004, conductor 1019, to the grounded conductor 722. Relay 1005 opens the operating circuit of relay 1004. Relay 1004 being slightly slow to release, maintains its armatures until relay 1005 is fully operated, at which time the following circuit is completed: battery through the left winding and contact of relay 1004, inner left back contact of relay 1020, winding of relay 1006, to ground at the front contact of relay 1005. Relay 1004 locks and relay 1006 operates in this circuit. The multi-contact relay 1002 is now operated in a circuit leading through the outer left contact of relay 1004, to ground at the contacts of relays 1006 and 1005.

Before proceeding to describe the operation of relay 1003, of the frame connector 1000, it may be well to discuss the release of the district frame and trunk connectors 900 and 901 which takes place before the relay 1003 is operated.

Release of the district frame and trunk connectors.—When the district selector 200 is operated to extend the trunk 102 through to the idle trunk 233, a circuit is closed for operating the release relay 707 in the marker. This circuit may be traced from bat-

tery, through the winding of said relay, conductor 735, right front contact of relay 820, thence over conductor 1021, through the trunk connector 901, conductor 235, thence 5 through the district selector switch 200, sleeve conductor 115 of trunk 102, to ground at the contact of slow-release relay 106. Relay 707 locks through its inner right contact, inner left contact of relay 708, to the 10 grounded conductor 722.

It may be noted at this time that the horizontal operating magnet 222 is also locked in a circuit from battery, through both its windings, thence through contacts 15 of the switch 200, to the grounded conductor 115. Therefore, this magnet will remain operated after the marker, which furnishes the operating circuit therefor, becomes released.

The release relay 707 operates the relay 20 708 in a circuit from battery, through the winding of relay 708, inner right contact of relay 709, outer right front contact of relay 707, outer right front contact of relay 706, to ground at the outer right back contact of relay 702. Relay 708 prepares a holding circuit for itself from battery, through its winding and inner right contact, winding of relay 709, to the grounded conductor 722. Relay 709, however, being 25 shunted, does not operate at this time.

The relay 707 in operating, removes ground potential from conductor 922, thereby causing the release of the frame connector 900 and the trunk connector 901 and 30 all relays associated therewith. The vertical operating magnets 210 and 212 and the special horizontal operating magnet 226 are also released. Thus the marker is disassociated from the district selector frame 200.

40 When relay 708 is fully operated, it opens the holding circuit of relay 707. This latter relay becomes released as soon as its original operating circuit has been severed by the trunk connector 901. Relay 707 in releasing, removes the shunt from the winding of relay 709 and this latter relay operates in series with relay 708 in the circuit above traced.

45 The relay 708 in operating, removes ground potential from conductor 817, whereby the operated test relays 800 are all released. Relay 709 operates the relay 710 in a circuit from battery, through the winding of relay 710, outer right front contact of relay 709, conductor 736, middle left contact of relay 810, conductor 825, outer right back contact of relay 707, outer right contact of relay 706, to ground at the outer right back contact of relay 702. Relay 710 operates and 50 closes a circuit for relay 711, traceable through the right contact of relay 710 to the grounded conductor 722. At the time relay 707 first operates, it opens the original holding circuit of relay 700. The relay 700, 55 however, remains energized in a substitute

holding circuit which may be traced from battery, through the winding and inner right contact of said relay, conductor 825, middle left contact of relay 810, conductor 736, outer right back contact of relay 709 (this latter 70 relay being deenergized at this particular time) to ground through the outer right contacts of relay 706 and relay 702. Before relay 709 can operate to open this substitute holding circuit, the original holding circuit 75 is replaced by the release of relay 707, which takes place prior to the operation of relay 709.

The relays 710 and 711 in operating, place the marker under the control of the office 80 trunk group relay 714, so that the marker through the agency of the frame connector 1000 and the trunk connector 1001 can determine the selection and testing of the proper group of trunks outgoing from the 85 office frame 300.

When ground is removed from conductor 817 as previously explained, relays 704, 809 and 808 become deenergized. When the frame connector 900 is released as explained, 90 relay 703 becomes deenergized. Relay 704 releases before relay 711 operates and therefore battery potential is maintained on conductor 734 to hold relay 1007 after its original circuit is opened. When the relay 707 95 operates, it opens the circuit of the district group relay 712 and this relay becomes released.

Operation of the office frame and trunk connectors.—The relay 1011 is now operated to initiate the operation of the trunk connector 1001. The circuit for this purpose may be traced from battery, through the winding of said relay, conductor 1022, contact of relay 714, conductor 738, front contact of relay 1004, upper front contact of relay 1006, to ground at the back contact of relay 1005, this latter relay having deenergized upon the operation of relay 1006. Relay 1011 causes the operation of relays 1010, 1012 and 1013 in the manner hereinbefore explained, resulting in the operation of multi-contact relay 1008. The multi-contact relay 1009 is now operated in a circuit from battery, through its winding, conductor 1023, contact of relay 714, conductor 739, right contact of relay 1010, to ground through the upper front contact of relay 1013, and the back contact of slow relay 1012. 110

115 The vertical magnet 309 controlling the row of contacts 311 in the office selector 300, is energized by means of a circuit traceable from battery, through the winding of said magnet, upper back contact of relay 313, thence over the tip conductor of the trunk 120 233, through the switch 200, left front contact of relay 107, through the sender selector 108, conductor 112, through the connector 500, conductor 521, normal contact of relay 130

703. inner left front contact of relay 710, conductor 740, through the frame connector 1000, to the grounded conductor 1019. Magnet 309 operates the bar 308 and prepares 5 the contacts in the vertical row 301. Magnet 309 also extends the circuit above traced through its contact and the winding of multi-contact relay 1003, to battery. Relay 1003 operates and completes a circuit for 10 relay 703 traceable from battery, through the winding of the latter relay, outer left front contact of relay 710, conductor 741, through contacts of the connector 1000, to the grounded conductor 1019. Relay 703 15 opens the energizing circuit of magnet 309 and relay 1003, but at its make-before-break contact completes a holding circuit traceable from battery, through the winding and contact of magnet 309, and in parallel from 20 battery through the winding and contact of relay 1003, contact of relay 1002, conductor 924, conductor 925, contact of relay 703, inner left front contact of relay 710, to ground as above traced over conductor 740. 25 *Testing the trunks at the office switch.*— The marker is prepared to make a test of the group of trunks appearing in the vertical row of contacts 304 at the office switch 300. This particular group of trunks is selected under the control of the office trunk 30 group relay 714. The selection consists in operating the vertical magnet 311 in a circuit from battery, through the winding of 30 said magnet, conductor 315, thence through 35 the frame connector 1000, conductor 1024, conductor 938, contact of relay 714, conductor 742, through the trunk connector 1001, to the grounded conductor 1019. The magnet 311 operates the vertical bar 312, preparing all contacts in the vertical row 304. 40 The testing operation takes place in substantially the same manner as that described in connection with the district selector switch 200. The testing relays 800 serve to test the successive trunks and the associated links in the office switch 300. The trunks 316, 317 and 318 may be considered as the last trunks in the group. Relay 805 relates to the trunk 318; relay 804 relates to the trunk 317, and 45 the relay for the trunk 316 is not shown. The preceding relays 801 to 803 may relate to preceding trunks in the group. It will be assumed that the trunk 317 is the first one in the group to be idle simultaneously 50 with the idle condition of its associated link 306. Accordingly, the relay 804 remains in a deenergized condition while all preceding test relays are operated. It will be understood that, analogous to the manner in which 55 the testing relays perform the test during the operation of the vertical magnet 212 of the district selector, these relays also perform a similar test during the period the vertical magnet 311 of the office switch is 60 being energized. Accordingly, by the time 65 the magnet 311 is operated in the circuit above traced, the relays 800 have assumed their set condition. When the magnet 311 is fully operated, it operates the relay 704 in the marker by means of a circuit from 70 battery, through the winding of said relay, normal contact of said relay, conductor 732, conductor 743, through the frame connector 1000, conductor 319, contact of magnet 311, to ground. Relay 704 locks in a circuit 75 through its winding and inner right front contact, inner right front contact of relay 711, to the grounded conductor 722. Relay 704 operates the relays 808 and 809 in circuits from 80 battery, through the windings of these latter relays in parallel, conductor 818, inner right contact of relay 704, to ground as just traced. Relay 826 is operated in a circuit from battery, through the winding of relay 812, thence through the winding of relay 85 826, left back contact of test relay 804, thence through the left front contacts of the preceding operated test relays, conductor 821, through the trunk connector 1001, conductor 1026, conductor 934, normal contacts 90 of relays 705, normal contacts of relay 707, right front contact of relay 704, to ground through the inner right front contact of relay 711 by way of conductor 722. Relay 826 operates and prepares for operation, the 95 horizontal magnet 320. 95 The operating circuit for the horizontal magnet 320 is now completed from battery, through the right winding of said magnet, conductor 321, through the frame connector 100 100 1000, conductor 1025, contact of relay 826, to the grounded conductor 817. It will be noted that conductor 817 is grounded through the inner right front contact of relay 711. Ground potential on this conductor also 105 serves to hold the operated test relays 800 in the manner hereinbefore described. The magnet 320 rotates the horizontal bar 322 and completes the connection of the trunk 233 through the switch 300 to the selected 110 idle trunk 317. Relay 313 is operated in a circuit from battery, through its winding, contact of switch 300, conductor 323, through the connector 1000, conductor 1027, inner front contact of relay 809, inner left 115 contact of relay 826, conductor 822, to the grounded conductor 817. Relay 313 operates and closes a locking circuit for itself and also for the horizontal magnet 320. The locking circuit may be traced from battery, 120 through both windings of magnet 320, contacts of switch 300, and in parallel thereto from battery through the winding and contact of relay 313, sleeve conductor 324, through contacts of the switch 200 to the 125 grounded sleeve conductor 115. The relay 313 completes the tip and ring conductors of the trunk 233 and opens the energizing circuit of the vertical magnet 309. 130

nectors and of the marker.—The connection having been extended through the district and office switches, the marker is no longer required and may now be released and returned to the common use of other lines. For this purpose, the release relay 707 is re-operated in response to the completion of the connection through the office switch 300. The circuit may be traced from battery, through the winding of relay 707, conductor 735, right front contact of relay 826, conductor 827; through the trunk connector 1001, conductor 326, through contacts of the switch 300, to ground over conductor 323 as previously traced. Relay 707 operates and locks temporarily through the inner right contact of relay 711. Relay 707 at its outer right back contact, opens the holding circuit of the relay 709 which releases. Relay 700 in releasing, removes ground from the conductor 722, thereby causing the release of the office frame connector 1000, the office trunk connector 1001, the relays associated therewith, the vertical magnets 309 and 311, and the test relays 800, together with the operated relays of the marker.

Prior to the time that the marker is disassociated from the sender as will presently be described, an indication is transferred from the marker to the sender, notifying the latter mechanism that connection has been completed through the district and office switches. This indication consists in operating the relay 414 in the sender by means of a circuit completed at the contact of relay 812. This circuit may be traced in detail from battery, through the winding of relay 414, conductor 425, through the connector 500, conductor 523, outer right contact of relay 711, conductor 744, to ground at the contact of relay 812. This circuit is not closed until the relay 812 operates a second time; namely, in series with the relay 826 preparatory to the operation of the office switch 300. The reason why said circuit is not completed when relay 812 operates the first time, namely in series with the relay 820, is because the relay 711 has not been energized at this time. Relay 414 locks through its left contact to the grounded conductor 421.

The marker may now be discharged from the sender, which release occurs as soon as the relay 700 becomes deenergized. Relay 700 in deenergizing as previously described, removes ground from conductor 718, and thereby opens the holding circuit of relays 501 and 502. Relay 502 in releasing, causes the release of relays 503, 509, 510, 511 and 508. Thus the marker is disassociated from the register sender.

From this point on, the connection may proceed in any suitable manner according to the class of the call concerned. If, for instance, the connection is one extending to a

distant office equipped with call indicators, the sender shown in the drawing may adjust itself in such a manner as to transmit impulses to the distant office to set the call indicator therein. After the sender has completed its function, a circuit may be completed for operating the sender release relay 410. Relay 410 opens the holding circuit of the impulse relay 400, which releases the slow relay 401. Relay 401 in turn releases the holding relays 402 and 416. These relays remove ground potential from the holding conductors to permit the release of the various energized relays in the sender.

The sender in releasing, also causes the release of the sender selector switch 108 and the relay 104, whereby the subscriber's line is completed through to the repeating coil 103. The manner in which the sender may cause the transmission of impulses to a distant office to further extend the connection or to operate a call indicator, and also the manner in which the sender releases, following the completion of its functions, are shown and described in general in the patent to S. B. Williams, No. 1,517,331, granted Dec. 2, 1924.

All trunks busy at the district selector.—It will be assumed that when the marker makes a test of the group of trunks outgoing from the district selector switch, all of these trunks are busy. Under such a condition it is desirable to release the marker from the sender and to re-associate the sender with the same or another marker for the purpose of making a new test of the trunks to ascertain whether or not, in the meantime, one has become idle.

Since all the trunks are busy, a circuit is closed for operating the busy relay 705 and may be traced from battery, through the left winding of said relay, conductor 746, through contacts of the district trunk connector 901, conductor 939, conductor 747, thence through the left front contacts of all the test relays in series, to conductor 821, thence to conductor 1015, through the trunk connector 901, conductor 934, normal contact of relay 705, normal contact of relay 707, inner right contact of relay 704, to the grounded conductor 817. Relay 705 at its make-before-break contact, opens the circuit just traced and closes a holding circuit as follows: battery, through its right winding and make contact, to ground as above traced. Relay 705 operates the relay 427 in the sender. The circuit for this purpose may be traced from battery, through the winding and normal contact of relay 427, conductor 428, through the connector 500, conductor 524, inner left contact of relay 705, to the grounded conductor 722. Relay 427 operates and locks through its winding and inner left contact to the grounded conductor 421. Relay 427 also operates the

relay 706 in the marker by means of a circuit from battery, through the winding of relay 706, conductor 748, through the connector 500, conductor 117, outer left front contact of relay 427, to ground over conductor 428 as traced. Relay 706 locks temporarily through its winding and inner left contact to ground at the contact of relay 700. Relay 706 at its outer right contact, 10 opens the locking circuit of relay 700. Relay 700, however, still remains energized under the control of the sender.

Relay 706 causes the operation of the release relay 411 in the sender. This circuit 15 may be traced from battery, through the winding of relay 411, which is slow to release, conductor 430, connector 500, conductor 526, left contact of relay 706, to ground at the contact of relay 700. Relay 411 20 moves ground from conductor 513, permitting the release of relay 700 and also the release of the connecting device 500. Relay 700 causes the release of the marker, and the release of the connecting device 500 25 disassociates the marker from the sender. The sender, however, remains in its same condition, ready to be associated with another or the same marker. The release of the marker also results in the release of the 30 connectors 900 and 901 and the disassociation from the selector switch 200, and also the release of the test relays 800.

It may be noted at this time that either the group of trunks outgoing from the district selector switch or from the office selector switch, may contain a number of trunks less than the total number of relays 800 provided for testing purposes. In such a case, it is necessary to artificially operate all test 40 relays in the series which do not correspond to actual trunks in the group. This is shown in connection with the office switch, although, of course, the same applies to the district selector. Assume, for example, 45 that the test relay 803 does not correspond to a trunk in the group outgoing from the office selector. Accordingly, this relay will be operated in a circuit from battery, through its right winding, lower back contact of relay 808, right back contact of relay 828, conductor 829, through the trunk connector 1001, to ground.

The next step is to re-associate the register sender with either the same or with another marker. After an interval following the disconnection of the sender, the slow relay 411 releases and ground is placed on conductor 513, causing the operation of relay 501 and the consequent operation of the connector 500 to associate the sender with an idle marker. As soon as the marker has been associated, the record stored up in the sender is transferred to the register relays shown in Fig. 6, where it is translated and 60 causes the operation of the group relays 712 and 714, for instance. In the same manner as hereinbefore described, the marker associates itself with the district selector 200 and with the proper group of trunks outgoing therefrom, and another test is made 70 thereof to ascertain whether or not some trunk has become idle in the meantime. If so, this trunk is selected and the connection is put through in the manner described.

The sender is equipped with a time-measuring device which commences to count time as soon as the sender has disassociated from the marker the first time upon finding all trunks busy. The interval counted may, of course, be varied arbitrarily and may provide sufficient time for making one, two, three or any required number of retrials. At the end of this interval, if an idle trunk has not been found, the sender refuses to proceed farther with the attempt and a busy 80 signal is transmitted to the calling subscriber. The timing device consists of the relays 431 and 432 and the interrupter 433.

As soon after the operation of the relay 427 as the interrupter 433 closes its upper 90 contact, relay 431 is operated in a circuit from battery, through its winding and normal contact, upper contact of interrupter 433, conductor 434, outer right front contact of relay 427, to ground at the contact 95 of relay 416. Relay 431 locks through its right front contact to the conductor 434. The interrupter 433 is so arranged that a considerable interval of time expires from the time it closes its upper contact until it 100 closes its lower contact. When this lower contact is closed, relay 432 is operated in a circuit from battery, through its winding and normal contact, left contact of relay 431, lower contact of interrupter 433, to the 105 grounded conductor 434. Relay 432 operates and locks to the grounded conductor 434.

The next time the marker finds all trunks busy following the operation of relay 432, a circuit is closed for operating relay 435. 110 This circuit leads from battery, through the winding and normal contact of relay 435, right front contact of relay 432, outer left contact of relay 427, to ground over conductor 428, as previously traced. Relay 435 115 operates and locks to the grounded conductor 420. Relay 435 operates the release relay 411 in a circuit from battery, through the winding of relay 411, left front contact of relay 435, to the grounded conductor 420. 120 Relay 411 operates and in the manner heretofore described, and causes the release of the sender from the marker. The relay 435 also causes the application of a source of tone current to the calling subscriber's line. 125 The circuit for this purpose may be traced from ground, through the winding of the tone device 436, outer right contact of relay 435, through the winding of the balancing coil 403, to ground at the contact of 130

relay 402. Current introduced in the winding of the balancing coil 403 produces tone in the calling subscriber's receiver, notifying him that the connection cannot be obtained. He thereupon hangs up his receiver, releasing relay 400 which in turn releases holding relays 401, 402 and 416. These relays remove ground potential from the various holding conductors, causing the release of the sender, the sender selector switch 108 and all associated apparatus which is being held.

All trunks busy at the office selector switch.—It may happen that the connection progresses regularly through the district switch 200, but that the marker encounters an "all trunks busy" condition at the office switch 300. In this event, the marker is similarly disconnected from the sender and the sender is associated with a new marker or the same marker, and another attempt is made to obtain an idle trunk at the office switch.

At the time the test is made of the trunks at the office switch, if all of them are found to be busy, the relay 705 is operated in a circuit from battery, through its left winding, conductor 746, through the office trunk connector 1001, conductor 1028, conductor 939, conductor 747, through the front contacts of the test relays 1001 in series, conductor 821, through the office trunk connector 1001, conductor 1026, conductor 934, to ground as previously traced. Relay 705 operates and locks through its right winding and contact, and in so doing operates the relay 427 in the sender. Relay 427 operates and causes the operation of relay 706 in the marker as previously described. Relay 706 in operating opens the locking circuit of relay 700 and completes an operating circuit for the relay 437 in the sender. This circuit may be traced from battery, through the winding of relay 437, conductor 438, through the connector 500, conductor 528, left front contact of relay 709, middle right contact of relay 706, to ground. Relay 437 operates and locks to the grounded conductor 421. Relay 706 also causes the operation of relay 411, which results in the release of the sender from the marker. Upon the release of the marker, all of the energized relays therein are deenergized.

The sender immediately associates itself with either the same or a new marker as soon as relay 411 becomes released, and preparation is made to make a new test of the group of trunks at the office switch. In this case, it will be necessary to omit the operation on the part of the marker in making a test of the district selector trunks and to place the marker in condition for testing the office trunks immediately. This is accomplished by operating the release relays 707, 708 and 709, together with the relays 710 and 711 in

the manner previously described in full. As soon as the marker is associated with the sender, the relay 725 is operated in a circuit from battery, through its winding, outer left contact of relay 705, conductor 749, 70 through the connector 500, conductor 118, left contact of relay 437, conductor 423, thence through the sender connector 500, conductor 719, left contact of relay 704, outer left contact of relay 708, to the grounded conductor 722. With the relay 725 operated, the operation of relay 907 is omitted and the release relay 707 is operated immediately. The circuit for this purpose may be traced from battery, through the winding of relay 707, conductor 735, front contact of relay 725, conductor 726, outer right contact of relay 604, conductor 640, connector 500, conductor 110, right back contact of relay 422, conductor 423, and thence to ground as above traced. 85 Relay 707 operates and locks through its winding and contact and the inner left contact of relay 708 to the grounded conductor 722. When relay 707 is fully operated, the relay 708 operates in a circuit from battery, 90 through its winding, inner right contact of relay 709, outer right front contact of relay 707, to ground. Relay 708 operates and completes a locking circuit from battery, through its winding and inner right contact, winding of relay 709, to the grounded conductor 722. Relay 708 in operating, opens the circuit of relay 707. Relay 707, however, does not release until relay 708 has closed its front contacts. Relay 707 then releases, and removing the shunt around the winding of relay 709, permits the latter relay to operate in series with relay 708. Following this, the relays 710 and 711 are operated and the testing relays 300 are connected to the trunks 105 of the desired group in the office switch 300, and a test is made thereof. If an idle trunk is found, the same is seized and a connection is extended therewith. On the other hand, however, if the trunks are all busy a second 110 time, the marker is released again and the sender subsequently either re-associates with the same or with another marker, and further testing is continued until the sender time measure has expired its interval, at 115 which time release takes place.

What is claimed is:

1. The combination in a telephone system of a group of trunks, a testing device, means for connecting said device to the trunks of 120 said group to make a simultaneous test thereof, means for causing the disconnection of said device from the trunks if all said trunks are busy, and means for thereupon causing the reconnection of said device to said group of trunks to make a repeated test thereof. 125

2. The combination in a telephone system of a group of trunks, means for extending a connection to said group, a testing device, means for connecting said device to the 130

trunks of said group to make a simultaneous test thereof, means for further extending said connection over the first idle trunk in the group, means for causing the disconnection of said device from the trunks if all said trunks are busy without releasing the extended connection, and means for thereupon causing the reconnection of said device to said group to make a further test thereof.

10 3. The combination in a telephone system, of a selective switch, a plurality of groups of trunks, a testing device common to all of said groups, means for connecting said device to any one of said groups of trunks for making a simultaneous test thereof, means for operating said switch to select the first idle trunk in the group tested, means for causing the disconnection of said device from the trunks if all said trunks are busy, and means for thereupon causing the testing device to be reconnected to said group of trunks to make a further test thereof.

4. The combination in a telephone system, of a plurality of switches, a plurality of groups of trunks each appearing in all of said switches, a marker common to all of said switches and common to all of said groups of trunks, means for connecting said marker to any switch to selectively operate the same and to any group of trunks to make a test thereof, means for causing the disconnection of said marker from the switch and from the group of trunks when all said trunks are busy, and means for causing the reconnection of said marker to the switch and to the group of trunks to make a further test thereof.

5. The combination in a telephone system, of a group of trunks, means for extending a connection toward said trunks, a plurality of testing devices, means for connecting one of said devices to the trunks of said group to make a test thereof, means for causing the disconnection of said device from the trunks of said group when all said trunks are found busy without disabling the extended connection, and means for thereupon causing the connection of either the same or another of said devices to said group of trunks to make a further test thereof.

6. In a telephone system, a plurality of switches, a plurality of groups of trunks each appearing in all of said switches, a plurality of markers each common to all of said switches and groups of trunks, means for connecting one of said markers to any one of said switches to selectively operate the same and for connecting such marker to any group of trunks to make a test thereof, means for causing the disconnection of the marker from the switch and from the group of trunks if all of said trunks are busy, and means for causing the connection of the same

or another marker to the same group of trunks to make a repeated test of said trunks.

7. In a telephone system, a selective switch, a group of trunks outgoing therefrom, means for extending a connection to said switch, a second selective switch, a second group of trunks outgoing from said second switch, a testing device, means for connecting said device to said first group of trunks to make a test thereof, means for further extending said connection over the first idle trunk in said first group to said second switch, means for connecting said testing device to the trunks of said second group to make a test thereof, means for operating said second switch to further extend the connection over the first idle trunk in said second group, means for causing the disconnection of said testing device from the trunks of said first group when all said trunks are busy, means for causing the reconnection of said testing device to said first group of trunks to make a repeated test thereof without releasing the extended connection, means for causing the disconnection of said testing device from the trunks of said second group when all such trunks are busy, and means for causing the reconnection of said testing device to the trunks of said second group to make a repeated test thereof.

8. In a telephone system, a group of trunks, means for extending a connection to said group, a register sender, a marker, means for connecting said marker to said register sender and to said group of trunks for making a test thereof, means controlled by said marker for further extending said connection over the first idle trunk in said group, means for causing the disconnection of said marker from the sender and from the group of trunks when all of said trunks are busy, and means for causing said marker to be reconnected to said sender and to said group of trunks to make a further test of said trunks.

9. In a telephone system, a selective switch, a group of trunks, a register sender, a plurality of markers, means for extending a connection to said switch, means for connecting said sender to one of said markers, means for connecting said one of said markers to said group of trunks for making a test thereof, means controlled by said marker for operating said switch to further extend the connection over an idle trunk in said group, means for disconnecting said one of said markers from said sender and from said group of trunks if all of said trunks are busy, and means for causing any one of said markers to be connected to said sender and to said group of trunks for making a further test of said group of trunks.

10. In a telephone system, a subscriber's line, a selective switch, a group of trunks, a

- register sender, a plurality of markers, means for extending said line to said switch and to said register sender, means for operating said sender over the subscriber's line, means 5 for connecting said sender to any one of said markers, means for connecting said one of said markers to said switch and to said group of trunks, means for setting said marker under the control of said sender, said marker 10 serving to make a test of the trunks of said group, means under the control of the marker in accordance with the setting thereof for selectively operating said switch to extend the subscriber's line over an idle one of said 15 group of trunks, means for causing the release of said one of said markers from the sender and from said switch and from said group of trunks if all of said trunks are busy,

and means for causing the reconnection of any one of said markers to said sender and to 20 said switch and to said group of trunks to make a further test of said trunks.

11. In a telephone system, trunks, means for extending a connection toward said trunks, a sender for recording designations, 25 a marker associative with said sender and operable in accordance with said designations for selecting and testing said trunks, means for releasing the marker when all of the tested trunks are busy, and means for again 30 bringing said marker into use for the purpose of making a further test of said trunks.

In witness whereof, I hereunto subscribe my name this 19th day of June, A. D. 1924.

EARL S. GIBSON.
